CANOE PADDLE

Robert A. Nichols, 613 3rd St. SW.,
Faribault, Minn. 55021

Filed Dec. 3, 1968, Ser. No. 14,776

Term of patent 14 years

Int. Cl. D12—14

U.S. Cl. D71—1

FIG. 1 is a top plan view of a canoe paddle embodying my design;

FIG. 2 is a side view thereof;

FIG. 3 is a partial section taken substantially along line 3—3 of FIG. 1; and

FIG. 4 is a transverse section taken substantially along line 4—4 of FIG. 1.

I claim:

The ornamental design for a canoe paddle, substantially as shown.
